UNITED STATES PATENT OFFICE.

LOUIS H. MAIER, OF NEW YORK, N. Y.

AUTOMATIC MUSICAL INSTRUMENT.

1,108,595. Specification of Letters Patent. Patented Aug. 25, 1914.

Application filed May 31, 1913. Serial No. 770,839.

To all whom it may concern:

Be it known that I, LOUIS H. MAIER, a citizen of the United States, and resident of New York city, borough of the Bronx, in 5 the county of Bronx and State of New York, have invented certain new and useful Improvements in Automatic Musical Instruments, of which the following is a specification.

10 My invention relates to improvements in player mechanisms for automatic musical instruments, and has particular reference to the installation of such mechanisms beneath the key bottoms of pianos, being especially adapted for use in grand pianos.

15 My invention comprises novel details of improvement and combinations of parts that will be more fully hereinafter set forth and then pointed out in the claims.

20 Reference is to be had to the accompanying drawings forming part hereof, wherein,

25 Figure 1 is an inverted plan view of a grand piano equipped with my improvements, the pumping pedal mechanism being partly omitted; Fig. 2 is an enlarged view of a portion thereof; Fig. 3 is a detail section on the line 3, 3, in Fig. 2; Fig. 4 is a section on the line 4, 4, in Fig. 2, showing the tracker box in the outward or operative

30 position; Fig. 5 is a similar view showing the tracker box in the closed or inoperative position; Fig. 6 is an enlarged detail plan view, illustrating means for moving the tracker box in and out of its recess in the key bottom, the tracker being omitted; Fig. 35 7 is an enlarged detail view substantially on the plane of the line 7, 7, in Fig. 6; Fig. 8 is an inverted view of part of Fig. 7; Fig. 9 is a section on the line 9, 9, in Fig. 8; Fig.

40 10 is a sectional view illustrating the pedal mechanism in connection with the tracker box; Fig. 10^a is a detail hereinafter referred to; Fig. 11 is a sectional detail of the power bellows shown in Fig. 10; Fig. 12 is a sectional view of the storage and expression bellows; Fig. 13 is a plan of a portion of Fig. 12; Fig. 14 is a plan view of the foot pedal mechanism; Fig. 15 is a detail of the parts 55, etc.

45 50 Similar numerals of reference indicate corresponding parts in the several views.

The numeral 1 indicates a piano casing shown in the form of a grand piano, and at 2 is the key bottom thereof, which, at the 55 forward portion, under the forward ends of

the keys, is provided with an opening 2^a, in which is fitted, to be moved in and out of said opening, a tracker box or frame 3, provided with a tracker bar 4, to the orifices of which the flexible tubes 5 lead in customary manner. Said tracker box and tracker and the location in a front opening of the key board are more or less similar to devices set forth in my Letters Patent No. 1,034,811, issued August 6, 1912, and my present invention relates to improved means for supporting and operating the tracker box, as hereinafter explained. The tubes 5 are shown leading to a bleed chest 6, secured to the key bottom in any suitable manner. Said chest (Fig. 5) is provided with a series of openings 6^a to which the several tubes 5 lead, and from the corresponding openings tubes 7 lead to the respective valves in the valve chests 8 of the striker pneumatics 9 of the player action, (Fig. 3). The bleed chest 6 has branch openings 6^b communicating, by relatively small orifices, with the vacuum chamber 6^c, covered by any suitable material 10, which chamber is connected by tube 11 (Figs. 1 and 2) with the suction storage bellows 12 of the player mechanism, which bellows is secured to the under side of the rear portion of the piano casing, as by the clips 13, (Figs. 1, 2). The suction storage bellows 12, provided with a suitable expression box and bellows 14, are connected by tubes 15 with the chests 9^a of the striker pneumatics 9. The suction storage bellows 12 is also connected by tube 16, suitably branched, to the pumping bellows 17 that are secured upon the under side of the key bottom and shown on opposite sides of the opening 2^a that receives the tracker box. The expression box and bellows 14 serve to reduce the tension that will operate upon the player action, and to cut off tension from the player action when the music sheet is being re-rolled over the tracker bar, in a well known manner, and as hereinafter described in connection with valve 62^a and tubes 65, 66.

55 My improved means for operating the pumping bellows 17 are illustrated in Figs. 1, 2, 10 and 14, whereby the foot pedals 18 may be folded under the key bottom and lowered to operative position, and whereby when the tracker box is moved inwardly or rearwardly in opening 2^a the pedals will be folded upwardly, and when the tracker box is moved outwardly to operating position the 110

pedals will be lowered. To this end I have shown a main frame 19, pivotally connected at 20 with the outer or lower portion of pedals 18, and movably suspended by links 21, 22 pivotally supported from the key bottom, as at 23, 24, on opposite sides of opening 2^a thereof. I have shown pivots 23, 24, as carried upon bars 25 secured upon the under side of the key bottom on opposite sides 10 of opening 2^a of the key bottom. The upper ends of foot pedals 18 are pivotally connected by links 26 with arms 27 (Figs. 1, 2 and 10) secured upon a rock shaft 28 suspended from the under side of the key frame, being 15 shown journaled in brackets 29, to which brackets the stationary board of bellows 17 is secured (Fig. 10), whereby said bellows is also suspended from the key bottom. Shaft 28 carries arms 30 shown extending 20 rearwardly beneath the key bottom and pivotally connected with links 31, which links are pivotally connected as at 32 with the movable board of bellows 17. The arrangement described is such that when the pedals 25 are lowered to the operative position in Fig. 10, the links 21 and 22 will assume substantially the same position, shown with the bellows collapsed, and when the pedals are depressed they will depress arms 27 by means 30 of links 26, thereby causing arms 30 to push links 31 upwardly and raise the movable board of the bellows. A suitable spring, indicated at 33 (Fig. 10), may be provided for causing the movable board of the bellows to 35 collapse, and thereby in turn to return the foot pedals to their normal upward positions. When the foot pedals are raised, to fold beneath the key bottom and tracker box, links 21 and 22 will swing rearwardly and 40 upwardly, substantially as shown by dotted lines in Fig. 10, causing the frame 19 and links 21, 22 to fold rearwardly, all snugly folded together under the key bottom. Any suitable means may be provided for retaining 45 the pedals and frame 19 folded upwardly under the key bottom and tracker box. This may be done by means of a suitable spring 34 secured to the tracker box and adapted to engage the forward portion of frame 19, as illustrated in Fig. 10^a, which spring may be readily released by hand from frame 19 and the latter allowed to descend by hand and be similarly raised into engagement with said spring. Any suitable spring 50 19^a may be connected with the frame 19 and key bottom to aid in counter-balancing the frame, if desired, as for easing the operation of raising and lowering the frame. I have 55 illustrated means for causing the frame 19 and pedals to be lowered when the tracker box 3 is drawn outwardly to the operative position, and for raising frame 19 and the pedals when the tracker box is moved inwardly to the inoperative position. To this 60 end I have shown arms 35 pivotally connect- 65

ed at their rear ends with links 21 and pivotally connected at their forward ends with the tracker box, as at 36, whereby when the tracker box is moved inwardly through opening 2^a of the key bottom, the arms 35 70 will push the links 21 causing frame 19 and the pedals 18 to be raised, and when the tracker box is moved outwardly the bars 35, by pulling upon links 21, will cause the frame 19 and pedals 18 to be lowered. The 75 arms 35, by means of the connection with the tracker box and with links 21, cause frame 19 and pedals 18 to be retained in the upwardly folded position when the tracker box is in the inward position, at 80 which time the spring 34 may be used in conjunction with the tracker box and frame 19 if desired. I have shown means for conveniently operating the tracker box to cause it to be moved inwardly and outwardly with respect to opening 2^a of the key bottom, whereby also arms 35 are actuated and the operation is made easy. To this end I have shown the bars 25 provided with side rails or flanges 25^a (Figs. 6 and 9) entering grooves 3^a in the sides of bars 3^b secured along the margins of the tracker box, whereby the latter is mounted to slide upon bars 25. Bars 25 are shown provided with racks 25^b in mesh with gears 36, carried by a shaft 37 90 journaled in suitable bearings in bar 3^b on the tracker box. The tracker box also carries means for rotating said shaft and gears, shown more clearly in Fig. 6, for which purpose I have illustrated a bevel gear 38 on shaft 37 in mesh with a corresponding gear 39 on shaft 40 journaled in suitable bearings on tracker box 3, and shown provided with a handle 41 at the forward part of the tracker box for rotating shaft 40. From this it will 95 be understood that when shaft 40 is rotated, gears 36 being correspondingly rotated will, by engagement with the racks 25^b, cause the tracker box to be moved inwardly or outwardly with respect to opening 2^a of the key 100 bottom, and whereby the operation of arms 35 and the movement of the pedals 18 and frame 19 is made relatively easy. 105 In order to lock the tracker box in the inward and outward positions I have shown a 115 shaft 42 journaled in bars 3^b on the tracker box, and provided with arms 43 having laterally disposed pins 44, (Fig. 6) which pins are guided in slots 45 in bars 3^b (Fig. 4), and said pins are adapted to engage 120 spaced slots 46 in flange 25^a (Fig. 6), whereby when the pins are in the upward position in said slots the tracker box will be locked in the inward or the forward position. To operate pins 45 I have shown 125 shaft 42 provided with a handle or arm 47 extending downwardly through the open bottom of the tracker box, in position to be conveniently operated beneath the latter, whereby shaft 42 may be rocked. 130

At 50 is a pneumatic motor, shown beneath the sounding board 1^b behind the key bottom, for operating the music spools *a* that are to be applied in the tracker box in any suitable manner. The crank shaft 51 of said motor is shown provided with a sprocket 52 over which passes a chain 53 receiving sprocket 54 on a telescopic shaft 55, 55^a, a suitable coupling at 56 serving to cause the parts of said shaft to rotate in unison while permitting their relative longitudinal movement as the tracker box is moved in and out. Shaft 55 is provided with a bevel gear 57 in mesh with a corresponding gear 58 secured on shaft 59 journaled in suitable bearings upon the tracker box. Shaft 59 carries a sprocket 60 to be connected by chain 61 for operation of the transmission mechanism of the music spool 20 contained in the tracker box, of any suitable or well known construction (not shown). By means of the telescopic shaft 55, 55^a, the gears 57, 58 may remain in mesh in either the inner or outward position of the tracker box, so that the shaft 55 is always ready for operating the transmission mechanism of the music spools.

As shown in Fig. 1, I provide a governor 62, and its tempo valve 62^b of any well known construction, shown connected by tube 63 to the motor, and said governor is shown connected by tube 64 to the source of supply in storage chamber 12. The tubes 65, 66 connect the valves of chamber 14 with the valves of the governor at 62^a, the latter being provided for controlling the rerolling of the music sheet and controlling expression of a composition being rendered. The governor is secured by any suitable means upon the under side of the casing below the sounding board. The tubes 67, 68 connect the valve mechanism in 62^a with any well known controlling device in the tracker box for re-rolling and expression (not shown).

The governor tempo slide 62^b is connected by a wire 69, having one end connected with a crank 70 on a rod 71, in a suitable bearing 72 upon the under side of the casing, and at 73 is a rod projecting through and rotatively carried by the tracker box, as in a bearing 74 thereon (Fig. 4). Said rod 73 is provided with a suitable finger lever 73^a whereby the rod may be rocked, which finger lever is shown passing upwardly through the tracker box in front of the music spools in convenient position for operation (Fig. 4). Rods 71 and 73 are slidably connected together, for which purpose I have shown a coupling 71^a connecting said rods, whereby rod 71 may be rotated by rod 73, in manner described with respect to the coupling 56, to operate rod 69 as required, in different positions of the tracker box.

At 75 is a hammer rest rail expression device secured upon the under surface of cas-

ing 1, and shown comprising three pneumatics provided with connections 76 for operating the hammer rest rails, which devices may be substantially similar to that shown in my Letters Patent No. 1,009,330, issued Nov. 21, 1911. At 77 is a damper raising pneumatic connected by rod 78 with the rail of the piano dampers, the latter constructed in any well known manner, the parts 75 and 77 being shown connected to the casing 1.

In Figs. 1, 2 and 3 I have shown the key operating mechanism actuated by the striker pneumatics 9, wherein the levers 80 are pivotally supported beneath the key bottom upon the rail 81, and are operated at their inner ends by push rods 82 pivotally connected with the striker pneumatics and with the levers 80. The forward ends of levers 80 are shown operating against pins or rods 83 guided in suitable guideways in the key bottom, adapted to push upwardly against the rear ends of piano keys 84. Suitable stops at 85, 86 (Fig. 3) are shown to provide the proper regulation between the rods 83 and keys 84, and to limit the movement of levers 80, which stops may be arranged in any suitable manner, or as shown in my Letters Patent No. 992,018, May 9, 1911.

Having now described my invention what I claim is:

1. An automatic musical instrument having a casing a key bottom, and a tracker in the plane of the key bottom, and provided with pumping bellows supported beneath the key bottom on opposite sides of the tracker.

2. An automatic musical instrument having a casing and a key bottom, a tracker supported within an opening in the key bottom, and pumping bellows carried by and below the key bottom on opposite sides of the tracker.

3. An automatic musical instrument having a casing provided with a key bottom having an opening at its front portion, a tracker, and means to support the tracker in said opening, combined with pumping bellows carried by the casing on opposite sides of said opening and tracker and substantially in the plane of the tracker.

4. An automatic musical instrument having a casing provided with a key bottom having an opening at its front portion, a tracker, and means to support the tracker in said opening, combined with pumping bellows carried beneath the key bottom on opposite sides of said opening and tracker and substantially in the plane of the tracker.

5. An automatic musical instrument having a key bottom, and a tracker box supported thereby combined with a pumping bellows beneath and carried by said key bottom on opposite sides of the tracker box, and substantially in the plane of the tracker.

6. An automatic musical instrument having

- a key bottom, and a tracker box supported thereby combined with pumping bellows beneath and carried by said key bottom on opposite sides of the tracker box, and substantially in the plane of the tracker, said bellows having the movable board uppermost. 5. The combination of a musical instrument having a key bottom, a pump carried thereby, links carried by said key bottom to fold under the key bottom, a pedal movably connected with said links, means movably connecting the pedal with the movable member of the pump, a tracker box mounted for movement relatively to the instrument, and means connecting said tracker box with one of said links for causing raising and lowering of the links and pedal to raise under the key bottom upon in and out movements of the 10 tracker box. 6. The combination of a musical instrument having a key bottom, a pump carried thereby, links carried by said key bottom to fold under the key bottom, a pedal movably connected with said links, means movably connecting the pedal with the movable member of the pump, a tracker box mounted for movement relatively to the instrument, and a link pivotally connecting the tracker box with one of the first named links to raise the links and pedal under the key bottom. 7. The combination of a musical instrument, a pump carried thereby, links carried by said instrument, a pedal movably connected with said links, an arm movably carried by said instrument and movably connected with the movable member of said pump, a link connecting said arm with said pedal, a tracker box movably supported by the instrument, and a link connecting the tracker box with one of the first named links for raising the pedal beneath the key bottom and for lowering it upon in and out movements of the tracker box. 8. The combination of a musical instrument having a key bottom, a tracker box, means movably supporting the tracker box upon the key bottom, and mechanism carried by the key bottom and tracker box for moving the latter in and out relatively to the former. 9. The combination of a musical instrument having a key bottom, a tracker box, means movably supporting the tracker box upon the key bottom, a rack carried by the instrument, a gear carried by the tracker box in mesh with said rack, and means upon the tracker box for operating said gear. 10. The combination of a musical instrument having a key bottom, a tracker box, means movably supporting the tracker box upon the key bottom, a rack carried by the instrument, a gear carried by the tracker box in mesh with said rack, and means upon the tracker box for operating said gear. 11. The combination of a musical instrument having a key bottom, a tracker box, means movably supporting the tracker box upon the key bottom, a rack carried by the instrument, a gear carried by the tracker box in mesh with said rack, and means upon the tracker box for operating said gear. 12. The combination of a musical instrument having a key bottom, a tracker box, means movably supporting the tracker box upon the key bottom, a rack carried by the instrument, a gear carried by the tracker box in mesh with said rack, means upon the tracker box for operating said gear, and means to lock the tracker box in an outward position relatively to the instrument. 13. The combination of a musical instrument provided with a key bottom having an opening in its forward portion, a tracker box adapted for movement within said opening, means movably supporting the tracker box at said opening, racks carried by the key bottom on opposite sides of said opening, gears carried by the tracker box and in mesh with said racks, and means upon the tracker box for rotating said gears. 14. The combination of a musical instrument provided with a key bottom having an opening in its forward portion, a tracker box adapted for movement within said opening, means movably supporting the tracker box at said opening, racks carried by the key bottom on opposite sides of said opening, a shaft carried by said tracker box, gears carried by said shaft and in mesh with said racks, a second shaft carried by said tracker box and provided with an operating handle, and gearing connecting said shafts. 15. A musical instrument having a key bottom provided with an opening at its forward portion, a tracker box adapted to fit within said opening, means movably supporting the tracker box at said opening, a shaft carried by said tracker box, arms carried by said shaft and provided with pins, said tracker box having slots receiving said pins, said key bottom being provided with openings adapted to receive said pins, and means upon said shaft for rocking the latter to actuate said pins. 16. A musical instrument provided with a motor and having a key bottom, a tracker box movably supported in an opening in said key bottom, and provided with means for supporting music spools, means upon the tracker box for rotating said spools, and a telescopic driving shaft connecting the last named means with said motor. 17. A musical instrument provided with a governor and tempo valve, a tracker box, means for movably supporting the tracker box upon the instrument, a telescopic rod connected with the tracker box, to rock thereon and extending in the direction of movement of the tracker box, and means connecting said rod with said tempo valve for operating the latter when the tracker box is in its outward position. 18. A musical instrument provided with a motor, a tracker box movably supported upon said instrument and provided with means for supporting music spools, means upon the tracker box for rotating said spools, and a telescopic driving shaft connecting the last named means with said motor, a governor and tempo slide carried by said instrument, a telescopic rod connected with said tracker box, and means connecting said

rod with said tempo slide for operating the latter when the tracker box is in an outward position.

19. A musical instrument provided with 5 a key bottom and sounding board, a tracker box supported within an opening in the key bottom, pumps beneath the key bottom on opposite sides of the tracker box, a pneumatic player action behind the key bottom, 10 and means operated by said action for operating the keys of the instrument.

20. A musical instrument provided with 15 a key bottom having an opening, and having a sounding board, a tracker box supported in the opening of the key bottom, pumps beneath the key bottom on opposite sides of the tracker box and said opening, a pneumatic player action behind the key bottom, means operated by said action for 20 operating the keys of the instrument, a motor carried by the instrument beneath the sounding board, a governor and tempo valve carried by the instrument beneath the sounding board, a combined storage and expression bellows carried beneath the sounding board, tubes connecting said bellows with said action and with said governor, and means connecting said bellows with said pumps.

30 21. A musical instrument provided with a key bottom having an opening and having a sounding board, a tracker box supported in the opening of the key bottom, pumps beneath the key bottom on opposite sides of 35 the tracker box, a pneumatic player action behind the key bottom, means operated by said action for operating the keys of the instrument, a motor carried by the instrument beneath the sounding board, a gov- 40 ernor and tempo slide carried by the instrument beneath the sounding board, a combined storage and expression bellows carried beneath the sounding board, tubes connecting said bellows with said action and with 45 said governor, means connecting said bel-

lows with said pumps, and expression controlling devices carried by the instrument beneath the sounding board.

22. The combination of a grand piano having a key bottom provided with an opening at its forward part, a tracker box mounted for movement in said opening, pumps beneath the key bottom, a pneumatic action beneath the sounding board and behind the key bottom, and levers beneath 55 the key bottom connecting said action with the piano keys.

23. The combination of a grand piano having a key bottom provided with an opening at its forward part, a tracker box 60 mounted for movement in said opening, pumps beneath the key bottom, a pneumatic action beneath the sounding board and behind the key bottom, levers beneath the key bottom connecting said action with 65 the piano keys, a motor supported beneath the sounding board, a governor and its tempo valve beneath the sounding board, a storage bellows beneath the sounding board, and tubes connecting said bellows with said 70 pumps and with the governor.

24. A musical instrument having a key bottom provided with an opening in its forward portion, a tracker box mounted for movement within said opening, a bleed rail 75 carried by the key bottom and provided with a plurality of bleed openings, flexible tubes connecting the tracker orifices with corresponding openings of the bleed rail, flexible tubes connected with said openings 80 of the bleed rail, and a pneumatic player action, the last named tubes being connected with the valves of said action.

Signed at New York city, in the county of New York, and State of New York, this 85 27th day of May, A. D. 1913.

LOUIS H. MAIER.
